Jefferson Riley

INVENTOR

BY Victor J. Evans

ATTORNEY

J. A. Wynn
WITNESS:

UNITED STATES PATENT OFFICE.

JEFFERSON RILEY, OF WEST DURHAM, NORTH CAROLINA.

SIPHON.

Application filed November 3, 1926. Serial No. 146,003.

This invention relates to a siphon, the general object of the invention being to provide means for siphoning water or other liquids from a bottle so that the water can be drawn from the bottle as desired, by simply opening a cock or valve at the lower end of the siphon.

A further object of the invention is to provide means whereby the siphon can be easily removed from one bottle and placed on another when the first bottle has become empty.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view showing the invention in use.

Figure 2 is a section on line 2—2 of Figure 1.

Figure 3 is a section on line 3—3 of Figure 1.

In these drawings, 1 indicates the siphon pipe which is of inverted U shape, with its shorter limb extending into the bottle A adjacent the bottom thereof and its other limb extending well below the bottom of the bottle, with this longer limb having its extremity bent at right angles, as shown at 2, where it is connected with a faucet or valve 3. A cross piece 4 is connected with the limbs adjacent the point where the pipe is bent to strengthen the device and one end of this cross piece rests upon the cap 5 of the bottle. A U-shaped spring 6 is held to the outer limb of the siphon by a bracket 7 which is connected to the limb by the eyes 8, the spring 6 gripping the bottle and thus holding the siphon firmly in place. I prefer

to place a resilient lining 9 on the inner face of the spring 6 and I may also coat the pipe with porcelain, as shown at 10 in Figure 2.

From the foregoing, it will be seen that the device can be easily and quickly connected with the bottle, and by applying suction to the mouth of the faucet, by means of a bulb or the like, the siphon action can be started and then it is simply necessary to open the faucet whenever desired to secure some of the contents of the bottle. When the bottle becomes empty, the device can be easily and quickly taken from the empty bottle and placed on a filled bottle.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with a bottle having a cap thereon, a U-shaped pipe having one limb passing through the cap and depending to a point adjacent the bottom of the bottle, the other limb depending to a point exteriorly of the bottle and below the bottom thereof, said second named limb being bent at substantially right angles at its lower end and being provided with a faucet at its outer end, said second named limb passing alongside of the contour of the bottle in close proximity thereto, a U-shaped bracket connected to said outer limb and having a U-shaped spring strip at the lower edge thereof bowed to embrace the contour of the bottle, said strip being of thin material and having an elastic lining on the inner surface thereof to contact with the bottle, a cross piece connecting the limbs adjacent the bend connecting the same and adapted to rest on the cap of the bottle.

In testimony whereof I affix my signature.

JEFFERSON RILEY.
